UNITED STATES PATENT OFFICE.

HERBERT LOUIS SELLE, OF WACO, TEXAS.

DESIGN FOR A SIGNBOARD.

Application filed June 28, 1927. Serial No. 22,587. Term of patent 3½ years.

To all whom it may concern:

Be it known that I, HERBERT LOUIS SELLE, a citizen of the United States, residing at Waco, in the county of McLennan and State of Texas, have invented a new, original, and ornamental Design for a Signboard, of which the following is a specification, reference being had to the accompanying drawing, forming part thereof.

I claim:

The ornamental design for a signboard as shown.

HERBERT LOUIS SELLE.
